UNITED STATES PATENT OFFICE.

FRANK W. SMITH, OF CHICAGO, ILLINOIS, ASSIGNOR OF ONE-FOURTH TO JOHN J. GLASHEEN, ONE-FOURTH TO RICHARD J. SNELLBERGER, AND ONE-FOURTH TO WILBERT J. LEWIS, ALL OF CHICAGO, ILLINOIS.

SMELTING MINERALS.

1,385,723.

Specification of Letters Patent. Patented July 26, 1921.

Application filed August 15, 1919. Serial No. 317,653.

To all whom it may concern:

Be it known that I, FRANK W. SMITH, a citizen of the United States, and a resident of Chicago, in the county of Cook and State 5 of Illinois, have invented certain new and useful Improvements in Smelting Minerals, of which the following is a full, clear, and exact description.

In lead smelting practice, it has been the 10 practice to draw the gases from the smelting furnaces by a blower and to force them through filtering bags to conserve the entrained dust and fume, generally known as "lead fume." It has been the practice to 15 periodically shake the bags to discharge the fume into compartments or chambers surrounded by high brick partitions and permit it to accumulate in the chambers and then ignite it by means of light waste, sufficient 20 air being admitted through doors and windows to furnish oxygen for combustion. It usually takes about three days after setting fire to the dust for the chambers to cool sufficiently before they can be cleaned, at 25 which time the dust becomes cindered and is in a columnar structure about six inches thick. During this period, the filter bags above the chambers are necessarily out of operation. This delay is caused by the 30 necessity of permitting the dust to cool off sufficiently so that it could be shoveled into wheel-barrows and dumped into railroad cars and taken to the blast furnace bin.

The object of the present invention is to 35 provide an improved method of handling this fume or dust which will avoid the delay and loss of time incident to the cooling of the fume in the firing-chambers.

Another object of the invention is to provide 40 an improved method by which the fume will be handled mechanically so that the men do not have to handle the burnt products, thus eliminating all danger of mineral poisoning.

The invention consists primarily in providing 45 hoppers in the fume-receiving chambers with valves, through which the hot cindered fume will fall, and discharging it, while it is hot and without waiting for it to 50 cool, onto a conveyer adapted to handle and convey it while hot into the usual railroad cars or place of storage. In this manner, the time, usually lost in waiting for the cindered material to cool and the gas to escape

therefrom until it is safe for the operators 55 to remove it, is saved and the receiving chamber can be used to again receive fume from the filtered bags. This practice results in greatly expediting the handling of the cindered fume. 60

The invention consists in the several novel features hereinafter set forth and more particularly defined by claims at the conclusion hereof.

In the drawings: Figure 1 is a longitudinal section of apparatus for practising the invention. Fig. 2 is a horizontal section taken on line 2—2 of Fig. 1, parts being omitted. Fig. 3 is a section taken on line 3—3 of Fig. 2. Fig. 4 is a section taken on 70 line 4—4 of Fig. 2 upon an enlarged scale.

The invention is illustrated in connection with a refining plant adapted for lead smelting practice and in which the gases are drawn from furnaces and discharged into 75 a flue passing along the bag-house 9. From said flue, the gases with entrained dust and fume are drawn through the filtering bags 10 of usual construction. As well understood in the art, mechanical shakers are operated at stated intervals to dislodge the material caught in the bags. 80

A chamber 14 is provided with downwardly convergent inclined walls 15 which direct the discharge from the bags onto 35 gates 16 which form a movable bottom for the chamber. The walls of the chamber are formed of concrete and the gates 16 are formed of metal to adapt the structure for burning the fume in the chamber. The 90 gates 16 are transversely slid able in guideways formed by channeled cross-beams 17 and 18, and are adapted to be opened and closed by chains 19 and shafts 20 which extend longitudinally of the chamber 15 and 95 are provided with wheels 21, so that the gates can be opened or closed by an operator outside of the chamber 14. The lower ends of walls 15 join with side walls 22 of a conduit 23 which contains an endless conveyer 24 which 100 is adapted to convey the material received from the chamber 14 to and through one end of the bag-house and to deliver the material into railroad cars 25 which are adapted to convey the fume to the blast furnace-bins. 105

The conveyer 24 is preferably of the endless chain type provided with metallic plates 30, the chains passing around sprockets 31

and 32 at the ends of the conveyer. A concrete floor 33 is provided under the conveyer. An electric motor 34 operates a belt 35 which in turn operates a pulley 36 on a shaft 37 which is connected by a chain 38 and sprockets 39 and 40 to the shaft 41 of the sprockets 31. The operation of the conveyer by driving mechanism is controlled by a suitable clutch 43 so that the operator can control 10 the operation of the conveyer as desired.

In the practice of the invention, the dust in chamber 14 is ignited in the usual way while it is in said chamber and while gates 16 are closed. As soon as the fume is burnt, 15 the gates 16 are opened and the fume, while it is still hot, is discharged upon the conveyer 24 which is adapted to conduct the material to the car 25 in that condition. As a result of this practice, the time heretofore 20 lost in waiting for the fume to cool sufficiently to make it possible to handle it by workmen and for the poisonous gases to escape will be saved, because as soon as the fume has been burnt, the conveyer can be 25 operated to remove this material and discharge it into the cars where it can be left to cool as long as desired without interfering with the operation of the plant.

The invention is not to be understood as 30 restricted to the details set forth, since these may be modified within the scope of the appended claims, without departing from the spirit and scope of the invention.

Having thus described the invention, what

I claim as new and desire to secure by Let- 35 ters Patent, is:

1. That improvement in smelting minerals which consists in filtering the gases from a blast-furnace, discharging the fume into a chamber, burning the burnt fume from the chamber before it has been cooled sufficiently to be handled by workmen and mechanically conveying it from beneath the chamber before it has so cooled, so that the filtering of 45 the gases may be continued without waiting for the fume to be so cooled.

2. In a smelting plant for minerals, the combination of means for filtering gases from a blast-furnace, a chamber beneath the 50 filtering means to receive the fume from the filtering means, means for controlling the discharge of the fume from said chamber, and mechanical means adapted to receive the hot fume discharged through said 55 controlling means and convey it away from the building containing the chamber.

3. In a smelting plant for minerals, the combination of means for filtering gases from a blast-furnace, a chamber beneath the 60 filtering means having a hopper therein for receiving the fume from the filtering means, gates for controlling the discharge of the fume from said hopper and an endless conveyer to receive the hot burnt fume dis- 65 charged through said gates and convey it to cars for transporting it to the smelter bins.

FRANK W. SMITH.
